UNITED STATES PATENT OFFICE.

LINNAEUS E. BAKER, OF FORT WAYNE, INDIANA, ASSIGNOR TO WAYNE COMPANY, OF FORT WAYNE, INDIANA, A CORPORATION OF INDIANA.

LIQUID-DISPENSING APPARATUS.

Application filed January 28, 1924. Serial No. 689,031.

My invention relates to improvements in liquid dispensing apparatus, particularly adapted for outdoor use.

One object of the invention is to provide a complete measuring pump apparatus in a permanently closed casing, instead of a casing which must be opened before the pump can be used.

Another object of my invention is to utilize the enclosing casing as a mounting frame for the operating mechanism.

Another object of my invention is to provide a structure pleasing and ornamental in appearance without sacrificing utility or convenience. Ample advertising space is also provided on the casing.

Another object of my invention is to provide a sturdy pump structure of minimum weight.

Another object of my invention is to provide a pumping apparatus the interior mechanism of which is readily accessible for adjustment or repair; and which it is very convenient to assemble and reassemble.

Another object of my invention is to protect purchasers of liquid therefrom against false measurement, by securely enclosing adjustable parts and official seals against unauthorized persons, and by providing safe-

guards against authorized operators who would be inclined to dishonestly manipulate such pumps.

With these and other objects in mind, the invention consists in a tubular casing enclosing the pump cylinder, upon which rests the flanged top cylinder head; a rack-enclosing tubular casing resting upon and supported by the flanged cylinder head; a flanged gear plate resting upon and supported by the rack casing; a tubular light post and counter mechanism and meter housing resting upon and supported by said flanged gear plate, and the rack driving mechanism adapted to this design.

My invention is shown in the best form known to me, in the accompanying drawings, in which:

Figure 1 is a side elevation of the complete liquid dispensing apparatus,

Fig. 2 is an edgewise elevation of the same,

Fig. 3, an enlarged detail, shows the means provided for giving access to the interior mechanism for reading the totaliz-

ing meter and for adjusting the counter and said meter.

Fig. 4, an axial section through the lower part of the pump casing, showing the interior mechanism,

Fig. 5, the upper part of the same, the discharge pipe being shown in full.

Fig. 6, a detail, is a section through the casing showing the upper and lower tie rods,

Fig. 7, a detail, shows an upper part of the lower casing, flange and upper casing broken away and a part of the top cylinder head in vertical section to show the strainer cup,

Fig. 8, an enlarged detail, is a section on line 8—8 of Fig. 1, and

Fig. 9 is an enlarged cross section on the line 9—9 of Fig. 2.

Referring now to the drawings, the casing of the liquid dispensing mechanism, or measuring pump, is formed of the lower section A, which encloses the pump cylinder, cylinder head, etc., an intermediate section A¹, which encloses the rack, stop mechanism, driving mechanism, etc., another intermediate section A², which encloses the counter and meter mechanism and forms the lamp post, and an upper section A³, which forms the lamp enclosure.

The section of the casing A has a door a to afford access to the electric conduit box b and the union p, hereinafter more fully described. This section of the casing is preferably cylindrical and made of suitable sheet metal, and rests upon and is secured to the base flange a². Upon its top rests the flange of the top cylinder head c¹, and the pump cylinder C is securely held between this head c¹ and the bottom cylinder head c by tie rods c² in the usual manner; while the liquid supply pipe P is secured to the bottom cylinder head by the union p. The top cylinder head c¹ is secured to the casing element A by tie-rods c³. A piston c⁴, piston rod c⁵, stuffing box c⁶ and rack c⁷ are all of any usual or convenient type. A filter screen cup c⁸ may be supplied in the top cylinder head, preferably with a clean-out plate c⁹ and with the discharge pipe c¹⁰, provided with valve c¹¹ leading to the overhead venting drain valve c¹². A draw-off cock c¹³ is provided to drain off waste liquid or solid matter kept back by the filter from the filter pocket in the top cylinder head.

The intermediate section A¹ of the casing is preferably made of suitable sheet metal in the form of a flattened tube, and for appearance sake may have its edges rounded 5 and its sides at the edges formed as a rounded bead. A¹ rests upon the top cylinder head, and after the gear plate E is placed on the top of A¹ said parts are held securely in position by tie rods c¹³.

10 Within the casing section A¹ is a stop rod D substantially parallel with the rack c⁷, with stops d, d¹, d², d³ and d⁴ thereon, and each of said stops is adapted to be rotated by a pull-rod d⁵ so as to bring it in line 15 with the lug c¹⁴ on the rack c⁷ in any usual or suitable manner for delivering the measured quantity of liquid desired. A washer c¹⁶ and set screw c¹⁷ limit the downward movement of the rack. A signal S is pivoted to a stationary part of the pump mechanism so as to be adapted to be seen through the window a⁴, in section A¹ of the casing when the lug c¹⁵ on the rack c⁷ engages the lever s, when the rack and piston are in 25 their lowest position shown in Fig. 4. A cover plate a⁷ affords access to the stop mechanism and seals, d⁶, and a cover plate a⁸ affords access to the stuffing box c⁶.

30 On the underside of the gear plate E are webs e, e¹, in which are journaled the driving shaft F, and the driven shaft f of the driving mechanism. This mechanism for driving the rack c⁷ upwardly for pumping, and downwardly to return the piston 35 to pumping position again, may be of any usual or convenient form. The one shown consists of a driving shaft F adapted to have axial movement, with loose gear f¹ thereon always in mesh with rack c⁷ and gear f² rotatable with the shaft f and always in mesh with said rack; a loose gear f³ on shaft F always in mesh with gear f⁴ fixed to shaft f; a handle f⁵ for rotating the shaft F; a clutch f⁶ on the inner hub of gear f¹, and another f⁷ on the inner hub of gear f⁸; a double clutch member f⁸ fixed to the shaft F between said clutches f⁶ and f⁷ and adapted to engage either of them, and a spacing sleeve f⁹ enclosing all said clutches. 45 A roller f¹¹ on pin f¹², journaled in webs on gear plate E, holds the rack c⁷ in engagement with the gear f².

50 The section A² of the casing, preferably made of suitable sheet metal, has on its lower part, preferably on either side thereof, a dial plate G, preferably held in position by screws, and a dial g. A pointer g¹ for each dial is driven and controlled by any usual or suitable mechanism, the one shown herein 55 being the subject of a separate patent application and is not herein described further than to state that it is driven from a pinion f¹⁰ fixed to the end of the driven shaft f.

Above the dials g—g are reflectors a³—a³ 60 with electric lights b¹—b¹ adapted to keep

the dials well illuminated at night. These lights are encased in glass cases b²—b² to maintain vapor proof enclosures in case of initial breakage.

A door a⁴ affords access to adjust the 70 counter drive mechanism to agree with rack travel; and the door a⁵ may be opened to read the totalizing meter M.

A hose fork a⁹ is adapted to receive and hold when not in use, the nozzle of the hose 75 not shown.

A conduit B for the electric light wires terminates at the bottom in a conduit box b, extends upwardly through casing sections A, A¹, and A² in which last, branches 80 lead off to the lights b¹—b¹ and terminates in the globe section A³, for supplying current to the light b³, which is also supplied with an encasing glass b⁴.

All the mechanism in sections A and A¹ of the casing are assembled, then the rack-driven mechanism is assembled on the under side and the meter and counter-driving mechanism on the upper side of the gear plate E, which is then placed in position and secured there by the nuts on the tie-rods c¹³. Then the section A² of the casing is placed in position and securely held there by cap-screws a⁶. The upper or lamp enclosing section A³ of the casing is seated 95 upon and secured to the section A² by thumb-screws a⁷.

A lock L, seated in a stationary part of the apparatus readily accessible to the operator, has a bolt l adapted to seat in a hole 100 f¹³ in a suitable part of the gear f⁴, preventing the operation of the pump by securing the whole rack-driving mechanism against rotation.

Obviously many changes may be made 105 without departing from the spirit of my invention, and I claim as within the scope of my invention any mechanism readable upon the claims finally allowed in this application.

I claim as my invention and desire to secure by Letters Patent of the United States: 110

1. A measuring pump having in combination, a pump cylinder, a closed tubular housing for said cylinder, a rack, stop mechanism, a section of tubular housing for said 115 rack and stop mechanism, driving mechanism, a substantially horizontal gear-plate to which the driving mechanism is secured seated upon the section of housing enclosing said rack and stop mechanism, and means for holding said housing sections and plate in fixed relation.

2. A measuring pump having in combination, a closed tubular housing composed of horizontally divided sections, and a substantially horizontal gear-plate to which the driving mechanism is secured, said plate secured between two of said housing sections. 125

3. In a service pump, a pump section 130

casing and two superposed enclosing casings aligned with and secured to the pump section casing, the last two casing sections being separated by a horizontal plate perforated to allow passage of the pump rack to the casing section, and means carried by the plate to actuate the rack.

4. In a measuring pump having a rack-actuated piston, a casing for said pump formed of a plurality of sections, a substan-

tially horizontal plate between the two casing sections perforated to allow reciprocation of said pump rack, rack-actuating means carried by said plate, and means for rigidly securing together said casing sections and plate.

In testimony whereof I have hereunto set my hand.

LINNAEUS E. BAKER.
